MERCURY-VAPOR PUMP FOR HIGH VACUUMS.

Application filed June 6, 1921. Serial No. 475,486.

To all whom it may concern:

Be it known that we, JULIUS JONAS, a citizen of the German Realm, residing at Meierhof, Baden, Switzerland, and OSKAR SEITZ, a citizen of the Swiss Republic, residing at Oberer Kappelerhof, Baden, Switzerland, have invented certain new and useful Improvements in Mercury-Vapor Pumps for High Vacuums, of which the following is a specification.

Various constructional forms of mercury vapor pumps have been proposed for producing high vacuums. Those pumps consist of a closed vessel containing mercury, provided with a pipe for connection to the preliminary vacuum pipe and a pipe for connection with the receiver, and in which, on the one hand, the mercury is vaporized by a heating device, and on the other hand the mercury vapor is condensed by a cooling device.

In operation, the flowing mercury vapor mingles with the air issuing from the receiver and binds it, and on condensing, gives it up again at that part of the vessel where the connection with the preliminary vacuum pump is situated.

The existing constructional forms of this kind of pump are more or less complicated, because the interior of the pump has contained hitherto guide partitions and covering plates and also cylindrical insertions, for the purpose of effecting the desired extraction by suction of the very smallest traces of air from the receiver. The idea that the kinetic energy of the flowing mercury vapor plays an essential part in sucking the air from the receiver, forms the basis of the present invention, which provides an air pump, the construction of which is extremely simplified compared with the known constructions.

The improved pump is based on the idea of utilizing as completely as possible the kinetic energy of the mercury vapor and guiding the mercury vapor in such a manner that it will reach the working point by the shortest way and in the proper condition of vapor. Further, in the improved form of the pump body resulting from this feature, the air supply place is so constructed and arranged that no mercury vapor is able to flow into the air supply pipe, thereby obviating the counteraction of all vagrant mercury vapors.

Experiments have shown that the use of one and the same chamber for the ascending mercury vapor and the dropping condensed mercury particles has considerable advantages as regards the working of the pump, and that it is distinctly disadvantageous to have a separate guidance such as is provided in the pumps hitherto known.

The use of the same chamber is not only a considerable simplification as regards the construction of the pump, but it also allows a better utilization of the supply energy both for increasing the volumetric output, as well as for increasing the pressure drop, in which, as already stated, the stream of vapor flows without being throttled, by the shortest and straightest possible path to the working point. The working chamber proper of the pump is thus divided into the mixing space and the condensing space, these spaces however are not divided sharply from one another but merge into one another.

The present invention has therefore for its object to provide a mercury vapor pump for producing high vacuums consisting of a closed vessel containing mercury which is furnished with a connecting pipe for connection with the preliminary vacuum pump and with a connecting pipe for connection to the receiver, and in which on the one hand the mercury is vaporized by a heating device, and on the other hand the mercury vapor is condensed by a cooling device, the arrangement being such that the flowing mercury vapor mingles with the air issuing from the receiver and binds it, but gives it up again on condensing at that part of the vessel where the connection of the preliminary vacuum pump is located.

Above the heating chamber there is provided for guiding the ascending vaporized mercury as well as the falling mercury drops, an internally unobstructed tube at the upper end of which the connection to the preliminary vacuum pump is located whilst the air to be drawn off is fed to the lower end of this tube, and a cooling device is provided between these two connecting points.

The construction of an improved pump according to this invention is illustrated diagrammatically in Fig. 1 of the accompanying drawings.

As shown, the main portion of the pump

is situated by the vertical vessel *a*, the lower and somewhat enlarged part of which contains a quantity of mercury *h*. This mercury is heated by a Bunsen burner *i*. The 5 mercury vapor flows upward through the tubular cylindrical part *k* of the vessel *a*, where it condenses on the cooled part *m* of the said vessel. For this latter purpose the part *m* is surrounded by a jacket *d* to 10 which the cooling liquid *g* is supplied at *e* and passes out therefrom at *f*. The upper end of the vessel *a* terminates in a tubular extension *c* to which the preliminary vacuum pump is connected at *o*. 15 Below the cooling jacket *d* a pipe *b* opens into the vessel *a* at right angles to the axis of the said vessel, approximately at the point where the mercury vapor assumes the form of mist, this point having been 20 found in practice to be the most favourable point on entry. The air which is sucked out of the receiver at *n* is thus caused at *l* to impinge approximately at right angles against the stream of mercury vapor and is carried 25 along by the latter.

After the mixture has traversed the cooling zone this air is released and is then sucked out at *o* by the preliminary vacuum pump. Instead of the Bunsen burner any 30 other sort of heat, for instance electricity, may be employed.

In this improved pump in which it is of importance to cause the mercury vapor to pass with great velocity by the shortest path 35 to the working point, that is to say into the condensing chamber of the pump, the intended purpose is effected in a high degree by constructing the air supply point in the manner shown in the figure.

40 The entire construction of the pump differs from what has been known hitherto also in this that in the improved pump the mercury vapor, instead of flowing from a narrow tube into a wide tube, flows on the contrary from a wide tube (the heating chamber) into a narrower tube (the mixing chamber and condensing chamber).

The density of the vapor thus becomes 45 great and consequently the attainable pressure-drop of the pump also increases. By the expression "pressure-drop" there is meant the pressure-difference between the preliminary vacuum pressure at which the high vacuum pump will just work fully, and the high vacuum attainable therewith.

This increase in the density of the vapor is permissible in this case because the pump tube is free from internal obstruction and therefore the vapor pressure can be converted without hindrance into motion. In 50 this motion, however, the vaporized condition does not remain the same. Whereas in the heating chamber the vapor is superheated, that is to say is dried, it is intended that 60 in the mixing chamber it shall already re-

sume the state of mist, and in the condensing chamber shall be cooled down to the point where the formation of drops begins.

It has been found that the most favourable mixing chamber consists only of a relatively small zone in which the intermingling of the mercury vapor and air is to take place. Outside this zone the vaporized condition of the mercury is less suitable for taking up the air because it is either still superheated or it has already become cooled too far, and therefore the admission of air must be effected in such a manner that the mingling process shall take place within the smallest possible space. 70

On account of the counteraction of the mercury vapor flowing into the air admission pipe, and inflow of air directed against the stream of mercury vapor does not come into question. An inflow of the air parallel 75 to the stream of mercury prolongs the mixing chamber because owing to the parallel movement of the vapor and of the air the inertia of the parts retards the mixing process.

The most favourable way is the inflow of 80 air at right angles, because this produces a rapid interpenetration of the two substances and the mixing chamber is extended only for a short length in the direction of the movement of the vapor.

90 The object of the apparatus to cause the kinetic energy of the mercury vapor to come into complete operation, and to convey the vapor into the condensing chamber with the least possible friction and by the shortest path, is thus considerably facilitated by admission of air at right angles. 95

Since the cooling device is situated outside the improved pump of this invention, a natural cooling action (in the atmosphere) 100 may be made sufficient to produce a good operation of the pump, especially when the pump is made of metal. This will depend upon the shape of the cooling surface, that is to say also upon the length of the pump tube. 110

If the pump tube is made of a length sufficient for effective cooling, then, as already mentioned hereinbefore, the admission of the air must take place at that point of the tube where the gaseous mercury vapor begins to assume the condition of mist. This arrangement is extremely suitable for the construction of a multistage or pump for producing a high vacuum with a great pressure-drop because it affords, in addition to simplicity in assembling the parts together, the further advantage that all the parts are suitable to the very last detail. 115

120 For effecting multistage working according to this invention a plurality, equal to the number of stages, of internally unobstructed tubes of different diameters for guiding the flowing mercury vapor, are arranged concentrically above the heating chamber in 125

such a manner that they are all traversed parallelly by the mercury heating chamber.

The lengths of the several tubes increase as their diameters decrease. The outermost

- 5 tube is connected with the receiver by means of a tubular neck which is inserted approximately at right angles into said tube, so that the inflowing air is mixed with the ascending mercury vapor in the space between the 10 two outermost tubes, in which space it is driven to the top where this annular space is closed to the outside, and admission apertures for the air that is released on the condensation of the mercury, are provided in 15 the inner adjacent annular space in which the rising mercury vapor binds again the released air, and leads it to the upper end of said space where the air, becoming again released, is led in the same manner into the 20 third annular space, and so forth, until the air which has been compressed several times by this means in the innermost tube is conveyed by the rising mercury vapor to the tubular neck (located at the upper end of 25 said tube) on its way to the preliminary vacuum pump; the parts of all the tubes serving to guide the gaseous mixture being cooled by a cooling device that is common to all.

- 30 This pump will now be described more fully with reference to the constructional example illustrated in Fig. 2.

In this figure *i* is the heating body; *h* is the mercury contained in the heating chamber; *a*, *a*₁, *a*₂, *a*₃ are the concentric guide tubes placed one into another for the ascending mercury vapor. The length of the tube *a*₃ is greater than that of the tube *a*, whilst the latter length is greater than the length 40 of the tube *a*₁, which last, finally, is greater than the length of the tube *a*. The annular spaces comprised between these tubes are closed at their other ends from the outside by caps *m*, *m*₁, *m*₂, *m*₃. At these points, 45 however, in each case there are provided apertures *o*, *o*₁, *o*₂, *o*₃ which allow the air to enter the next inner annular space.

The outermost tube *a* is provided with a pipe neck *b* which is set at right angles to *a* and is connected with the receiver.

Thus the air *l* from the receiver flows through the aperture *n* into the pipe neck *b* and from the latter into the annular space which is bounded by the tube *a* and the tube *a*₁ and in which mercury vapor ascends.

The mercury vapor binds the inflowing air and carries it up to the upper end of the annular space. Since, however, the tube *a* is cooled at its portion situated at the pipe neck *b* and above the same by the liquid *g* flowing through the cooling device *d*, the mercury vapor becomes condensed on the sides of the tube *a*, but only the compressed air passes through the apertures *o* into the 60 next inner annular space enclosed between 65

the tubes *a*₁ and *a*₂. Since mercury vapor is ascending also in this latter space, the operation will be repeated in the same manner as often as there are steps in the pump.

The compressed air ascending in the innermost tube *a*₃ passes finally into the pipe neck *c* whose upper end has an opening *o*₃ through which the multistage compressed air enters the pipe leading to the preliminary vacuum pump.

75 It is to be noted that the mercury condensed in the several spaces runs down freely back into the heated mercury vessel so that it is always the same substance that circulates between vaporization and condensation.

80 This improved pump constitutes an interesting series arrangement of a plurality of pumps hereinbefore described, in which all the pumps combined in this manner have a common heating device, a common heating chamber, a common body of mercury and a common cooling device, and it is an extremely favourable feature that the cooling water which flows in through the pipe neck *e* and 85

out through the pipe neck *f* first flows round the tube *a* into which the air enters from the receiver. The pipe neck *b* is cooled as well and this is a very important feature because 90

95 first it prevents the entry of mercury vapor into the receiver, and second the zone in which the mercury vapor assumes the form of mist is thereby located exactly at the point of admission of the air. Since the

100 pressure-drop is considerably increased in the manner above described by means of the multistage air pump, a considerably smaller preliminary vacuum pump may be employed, and in some cases even very simple jet pumps will be found sufficient. In the

105 present case it is particularly advantageous to employ as a preliminary vacuum pump a water jet pump which is fed with the cooling water of the high vacuum pump discharging through the pipe neck *f*, so that the 110

water that is used is made to serve a double purpose.

An especially advantageous construction of the improved pump is provided by a conical formation of the internally unobstructed 115

tube, the connection to the preliminary vacuum pump being made at the apex of the cone. The conical pump body thus stands with a wide aperture upon the heating chamber and tapers in the upward direction.

The connecting pipe for the air to be sucked away is inserted from the side into the lower and wider portion of the mantle of the cone. The advantage of this arrangement is that, owing to the tapering 125 of the tube, the effectiveness of the cooling increases in the upward direction so that no mercury will pass over into the pipe leading to the preliminary vacuum pump. In this manner the pump chamber is pre- 130

vented from becoming impoverished in mercury so that the pump can be worked with a comparatively small quantity of mercury.

The use of a small quantity of mercury ⁵ also prevents the drawbacks of a retarded ebullition and thus a high efficiency is attained.

The improved pump is illustrated diagrammatically in section in Fig. 3 where-
¹⁰ in:-

H is the heating chamber of the pump;

Q is the mercury;

F is the heating device;

P is the conical pump chamber;

¹⁵ B is the admission pipe for the air flowing into the pump;

R is the point of connection to receiver;

O is the inlet aperture into the pump chamber for the air coming from the receiver;

V is the outlet aperture from the pump chamber for the air sucked by the vacuum pump;

W is the cooling liquid; and

²⁵ K is the cooling vessel with the inlet Z and the outlet A for the cooling medium.

As shown in the figure, the conical pump body tapers towards the air outlet so that the cooling acts very energetically at the ³⁰ end of the condensing operation.

This arrangement prevents entirely any mercury from passing out of the pump chamber. In this modification it is an advantage that the pipe B is also surrounded ³⁵ by the cooling liquid.

For the purpose of getting a comparatively small mixing chamber for mixing the sucked-in air with the mercury that passes over in the form of mist, it is, as already ⁴⁰ stated, an advantage to lead the air to the pump tube in a direction at right angles to the direction of movement of the mercury vapor. The efficiency of the pump is increased by the intensive interpenetration of ⁴⁵ the two substances in a comparatively small space. This circumstance also allows of reducing the total height of the pump and of rendering its construction more economical.

The air coming from the receiver requires, ⁵⁰ however, a wide leading-in pipe in order to get a large volumetric efficiency of output. If a tube of circular cross-section is employed as the leading-in tube, then in that case when the inflow of the air is at right angles, there will be a circular inlet into the pump chamber, the cross-section of which inlet is equal to the cross-section of the wide leading-in pipe. This shape of large inlet diminishes very considerably the ⁵⁵ efficiency of the pump. On the one hand a considerable quantity of mercury vapor which is still expanding notwithstanding its high velocity, enters the leading-in pipe and thereby counteracts in a considerable degree ⁶⁰ the effectiveness of the pump. On the other ⁶⁵

hand the mixing chamber necessitated by this relatively high inlet, is so great that the condition of the mercury vapor is not in all parts of the mixing chamber the very best for carrying with it the maximum quantity ⁷⁰ of air, so that the efficiency must be smaller on this ground also.

According to this invention the air admission pipe has still a relatively large circular cross-sectional area, but just before ⁷⁵ it opens into the pump, whilst retaining or having its cross-section increased, it assumes a shape such that the inlet will have a smaller extent in the direction of the movement of the mercury vapor than in a direction at right angles thereto. By this means, first the entry of the mercury vapor into the air admission pipe is prevented in a practically sufficient degree, and second the mixing chamber is reduced to a smaller size ⁸⁰ which is of advantage for the operation and the size of the pump.

A constructional example of this modification of the improved mercury vapor vacuum pump is illustrated in Figure 4 in ⁹⁰ which:-

H is the heating chamber of the pump;

Q is the mercury;

F is the heating device which may also be of electric nature;

P is the pump chamber;

V is the pipe for connection to the preliminary vacuum pump;

R is the pipe for connection with the receiver;

B is the admission pipe of circular cross-section for the air to be sucked away by the pump;

C is a portion of the pipe B just before ¹⁰⁵ it opens into the pump;

O is the inlet for the air.

As shown in this figure, the entry of the air into the pump chamber takes place in a direction at right angles to the direction of the movement of the mercury vapor. ¹¹⁰ Inlet O is of rectangular shape with, according to this invention, the short side of the rectangle having the same direction as the direction of movement of the mercury vapor.

The cross-section of the pipe changes from the circular shape into the rectangular shape in the direction C of the pipe. K is the cooling vessel which surrounds both the upper part of the pump and the pipe B. W is the cooling liquid which enters at the point Z into the cooling vessel K and passes out from the same vessel at the point A.

The constructional example shown in ¹²⁵ this Fig. 4 has further important advantages.

In the first place it is to be noted that the end C of the pipe which is at right angles to the direction of movement of the ¹³⁰

mercury vapor, is a certain length which is indispensible for the proper working of the pump. The end C of the pipe must be of such length that no expanding mercury vapor particle can enter the pipe B without first having struck against the upper wall of the end C of the pipe. By this striking the kinetic energy of the particle is reduced to such an extent that the current of air passing through the pipe B is not obstructed in any way by a counter-acting flow of mercury vapor.

A further advantage is to be found in the U-shape formed by the air admission pipe B and the pump tube P, so that the pipe and the pump have actually the form of two communicating pipes.

For the reasons already stated, it is possible only with the provision of a sufficiently long length C to carry the pipe B vertically downwards. In other respects the requisite length is kept comparatively small by constructing the inlet O in the manner described.

The illustrated U-shaped arrangement allows on the one hand the use of a common cooling vessel for the air admission pipe and pump into which the entire apparatus is immersed, and on the other hand a convenient connection to the receiver and to the preliminary vacuum pump, because both connections can be located side by side in the top or cover of the cooling vessel.

The cooling device is intended, as already stated, to cool the pump tube between the inlet and outlet for the air. The flat shape of the inlet O and of the end C of the pipe entails the risk that, especially in the case of a pump made of metal, the cooling will act too far downwards, that is to say, actually upon the heating chamber. This premature cooling of the ascending mercury vapor is injurious and reduces the effectiveness of the pump.

In the improved construction therefore, the cooling device is made of such a size that it will act upon the pump tube and the air admission pipe in such a manner that the gaseous mercury vapor will assume the form of mist only after it has reached a point above the heating chamber.

What we claim is:—

1. A mercury vapor pump for obtaining high vacuums, including a closed vessel containing mercury, a pipe for connection to a preliminary vacuum pump, and a pipe for connection with the receiver, i. e., the chamber to be exhausted, a chamber in which the mercury is heated by a heating device, a cooling device for condensing the mercury vapor, characterized by the feature that above the heating chamber there is provided as a guide for the ascending vaporized mercury and also for the falling

drops of condensed mercury, an internally unobstructed tube at the upper end of which is located the connection to the preliminary vacuum pump, whilst the connection to the receiver is made at the lower end of said tube; the cooling device being located between these two points of connection.

2. A mercury vapor vacuum pump as claimed in claim 1, characterized by the feature that the pipe conducting the air from the receiver to the pump enters the pump in a direction at right angles to the direction of the flow of the mercury vapor.

3. A mercury vapor vacuum pump as claimed in claim 1 or claim 2, characterized by the feature that the cooling device is the wall of the internally unobstructed tube located above the heating chamber and the pipe leading the air out of the receiver enters the said tube at that point of said tube where the gaseous mercury vapor begins to assume the form of mist.

4. A mercury vapor vacuum pipe as claimed in claim 1, including a plurality of internally unobstructed tubes of different diameters serving to guide the flowing mercury vapor, the said tubes being arranged concentrically above a common heating chamber in such a manner that they are all traversed in the same axial direction by the mercury vapor generated in the said common heating chamber; the lengths of said tubes diminishing with their respective diameters, the lower part of the outermost tube being connected to the receiver by a tubular neck inserted approximately at right angles, the annular space between the adjacent tubes being closed at its upper end, except for an aperture in said upper end connecting each annular space to the next towards the axis, the preliminary vacuum pump connection being located at the upper end of the innermost tube; the parts of all the tubes serving to guide the gaseous mixture being cooled by a cooling device that is common to all said parts.

5. A mercury vapor vacuum pump as claimed in claim 4, characterized by the feature that the preliminary vacuum pump, consists of a water jet pump which is operated by the water that serves to cool the high vacuum pipe.

6. A mercury vapor vacuum pump as claimed in claim 1, characterized by the feature that the internally unobstructed pump tube located above the heating chamber is made conical and is seated with its wide end upon the heating chamber, the connection to the preliminary vacuum pump being located at the apex of the cone, and the connection with the receiver being located laterally and above the heating chamber.

7. A mercury vapor vacuum pump as

claimed in claim 6, characterized by the feature that both the conical surface of the pump tube and the admission pipe for the air coming from the receiver are cooled.

5 8. A mercury vapor vacuum pump as claimed in claim 7, characterized by the feature that the pump itself and the admission pipe for the air coming from the receiver are both cooled in a common cooling 10 vessel.

9. A mercury vapor vacuum pump as claimed in claim 1, characterized by the feature that the pipe conducting the air from the receiver to the pump is constituted by 15 a tube of relatively large, preferably circular cross section, which shortly before its aperture into the pump, assumes a shape of equal or increased cross section such that its said aperture is of less extent in the direction of the movement of the mercury vapor than in a direction at right angles thereto. 20

10. A mercury vapor vacuum pump as claimed in claim 9, characterized by the fea-

ture that the air admission pipe for the air to be sucked away, forms with the pump tube a U-shaped device; the modified end of the air admission pipe being arranged at right angles to the direction of the movement of the mercury vapor and being made of a length such that no expanding mercury vapor particle is able to enter the descending portion of said air admission pipe without first having struck against the upper wall of said end of said air admission pipe. 25 30

11. A mercury vapor vacuum pump as claimed in claim 1, characterized by the feature that the cooling device is so constructed that it acts upon the pump tube and the point of admission of the air in such a manner that the gaseous mercury vapor does not assume the form of mist until after 40 it has arrived above the heating chamber.

In testimony whereof we have signed our names to this specification.

JULIUS JONAS.

OSKAR SEITZ.
